BUSSELL R. SMITH, WILLIAM F. SONGER, AND LAMBERT A. SALENDER, OF ASHLAND, KENTUCKY, ASSIGNORS TO THE AMERICAN ROLLING MILL COMPANY, OF MIDDLE-TOWN, OHIO, A CORPORATION OF OHIO

SHEET METAL ROLLING

Application filed December 29, 1930. Serial No. 505,260.

Our invention relates to the rolling of sheet metal, and particularly to an arrangement of mills and heating furnaces directed to the production of finished material, which material is also useful for the rolling in greater multiples of thickness to finer gauges.

With the discovery that it was possible and practical in continuous rolling processes to reduce wide, thin metal to sheet 10 form by forming in a pass or passes of one mill a succession of pieces which had a cross sectional contour which could readily be equally reduced in all portions thereof in a succeeding mill, the art has directed its attention to accomplishing some of the advantages of continuous rolling by the use of less expensive equipment.

The invention in this application is directed to such an end, and deals with a mechanism and method which can be employed to 20 form sheets from sheet bars at a single heating. The subject matter of this application is touched upon and its basic principles covered in our co-pending application Serial

25 No. 429,297, filed February 18, 1930.

The particular problem with which this application deals is the the production from sheet bars of sheets, which at present we have been able to produce as thin as 18 gauge, 30 and also the production of what has been termed "break down", namely, material which can be formed into packs, and will be uniform enough to permit of a finishing rolling operation without any shaping pass 35 in the finishing mill of the material from which the pack is formed.

Another way of stating our object is that we propose to start with the usual sheet bar of commerce, and at a single heating produce a product which is closely similar to the product of the continuous, four-high, roller bearing mills of the present day.

We accomplish our novel method, employing the mechanism shown in the accompanying drawing, and will fully describe both the method and the mechanism. In the appended claims we will set forth the novelty of our invention.

In the drawing:—

50 Figure 1 is a side elevation, partly dia-

grammatic, of an arrangement of rolling mills, tables and furnaces.

Figure 2 is a section on line 2—2 of Figure 1.

Figure 3 is a plan view of the mills and 55 tables.

While the particular nature of the arrangement of mechanisms shown is not essential to our invention, we have selected for illustration a standard set-up, which will serve for accomplishing our objects. 60

We have indicated a furnace at 1, which will preferably be a continuous furnace, into one end of which sheet bars 2 are placed, and from which the sheet bars properly heated are fed one by one. Located adjacent to the outlet of the furnace is the table 3 of the two-high mill 4. By preference, this mill is kept cool by water, as by a spray 3a, and is what is known as a water mill. 65

As the sheet bars are fed from the furnace, they are passed in succession through the two-high mill, and fall onto the catcher table 5. The catcher immediately passes the rolled bars over the top of the two-high mill to the roller, so that the bars are rolled down by the "under and over" method, 70 which is a very rapid operation. 75

When the bars have been sufficiently roughed down, they are passed by the catcher, without any reheating, to the table 6, which is the entering table for the three-high mill 7. This mill has a small diameter middle roll, and is designed to produce thin sheet metal, being rigid, wide, and also kept 80 cool with water, as by a spray 7a. 85

It is not practical to pass sheet bars directly to a three-high mill because they are too short to manipulate. This is the reason for the preliminary passing through the two-high mill. 90

In the three-high mill 7, the roller introduces the roughed out plates, which are furnished from the two-high mill, either first singly, or first in packs of two or more, which 95 he assembles on the table of his mill.

The piece when passed through the lower and middle roll of the three-high mill, is ejected onto the tilting table 8. This table may be automatically operated or operated 100

by a catcher. The piece when it passes onto the table is fed by means of the table, or, if the table is not automatic, is manipulated by the catcher so that it passes back to the 5 roller between the working or middle roll and the large upper roll of the mill 7.

The entrance table 6 of the three-high mill is of special construction in one respect. We have shown a chain conveyor 6a, in a dia- 10 grammatic manner, since any feed table will be satisfactory. The important point is, that located along the table at one side thereof only, is a side guide plate 6b. Since, as it will be recalled, the roller is called upon to 15 roll packs on this three-high mill, and to perform his work with rapidity, the use of this side guide is important.

What occurs is, that as the piece or pack comes through the mill above the central roll, 20 it will fall on the feed table which urges it toward the bite of the lower and middle rolls. The operator grasps the pack with his tongs as it comes out over the feed table, and jams it up against the side guide. He then lets 25 go of the pack and it feeds accurately and regularly into the mill.

If the pieces are in the form of packs when first introduced in the mill 7, then the rolling continues to and fro in the manner noted 30 until the desired gauge is reached. If the pieces are first passed through the mill in single thickness, they are given a pass or so in the single, and are then assembled into 35 packs by the roller, whereupon the rolling continues in packs.

We have found, in preparing rough plate for a further rolling operation, that around 16 gauge is a good thickness for the finished 40 product, and we can readily accomplish this, and we can, with the types of mechanisms noted, produce rough plate having a very uniform cross section and thickness. Also, we have rolled 18 gauge sheets on this set- 45 up, same being a commercial product.

Preferably we impart to the rough plate 50 when this is what we are making, by a control of the various factors entering into the active passes in the several operations, a pre-arranged cross sectional contour, which is somewhat convex.

The rough plate produced will have the desired width of the final product, same being provided for in cutting the sheet bar; it will also have its convexity extending length- 55 wise of the direction in which the assembled pieces are to be further rolled, which makes it possible for the final rolling to be done expeditiously.

Having thus described our invention, what 60 we claim as new and desire to secure by Letters Patent, is:—

1. The combination for the purpose de- 65 scribed of a furnace, one two-high mill with its tables, and one three-high mill with its 70 tables.

2. The combination for the purpose de- 75 scribed of a continuous furnace, one two-high mill arranged for rolling sheet bars in pairs by under and over method, and one three- high mill having a small central roll arranged for producing sheets.

3. The combination for the purpose de- 75 scribed of a continuous furnace, a two-high mill arranged for rolling sheet bars in pairs by under and over method, and a three-high mill having a small central roll arranged for producing sheets, and a tilting table for the three-high mill.

4. The combination for the purpose de- 80 scribed of a furnace, a two-high mill with its tables, and a three-high mill with its tables, the outlet table of the three-high mill being a tilting table.

5. That process for forming rough plate 85 for a succeeding rolling operation, which consists in starting with heated sheet bars, then by under and over method rolling out the sheet bars, and without reheating passing the product of this rolling to and fro between the rolls of a three-high mill having a small central working roll.

6. That process for forming rough plate 90 for a succeeding rolling operation, which consists in starting with heated sheet bars, then by under and over method rolling out the sheet bars, and without reheating passing the product of this rolling to and fro between the rolls of a three-high mill having a small central working roll, and so arranging the active 95 passes in the three-high mill as to produce material which has a substantially uniform thickness and cross sectional contour.

7. That process for forming rough plate 100 for a succeeding rolling operation, which consists in starting with heated sheet bars, then by under and over method rolling out the sheet bars, and without reheating passing the product of this rolling to and fro between the rolls of a three-high mill having a small central working roll, and so arranging the active 105 passes in the three-high mill as to produce material which has a substantially uniform thickness and cross sectional contour, said cross sectional contour being convex in the direction of rolling.

8. The combination for the purpose de- 110 scribed of a furnace, one two-high mill with its tables, and one three-high mill with its tables, both of the said mills being kept cool by application of water thereto.

9. The combination for the purpose de- 115 scribed of a continuous furnace, one two-high mill arranged for rolling sheet bars in pairs by under and over method, and one three-high mill having a small central roll arranged for producing sheets, both of the said mills being kept cool by application of water thereto.

10. The combination for the purpose de- 120 scribed of a continuous furnace, a two-high mill arranged for rolling sheet bars in pairs 125

by under and over method, and a three-high mill having a small central roll arranged for producing sheets, and a tilting table for the three-high mill, both of the said mills being kept cool by application of water thereto.

11. That process for forming rough plate for a succeeding rolling operation, which consists in starting with heated sheet bars, then by under and over method rolling out the sheet bars, and without reheating passing the product of this rolling to and fro between the rolls of a three-high mill having a small central working roll, at least the concluding passes in the three-high mill being with the material in two thicknesses.

12. A three-high mill for pack rolling comprising two large backing up rolls and a smaller diameter central working roll, a feed table at the entering side of the mill, and a 20 single side guide for said feed table on the opposite side from the position where the operator stands, for the purpose described.
